RICHARD HERBERT PARFITT, OF EAST GREENWICH, ENGLAND.

PATTERN-CYLINDERS OR THE LIKE FOR USE IN CONNECTION WITH THE MANUFACTURE OF INLAID LINOLEUM OR OTHER SIMILAR MATERIAL.

1,090,496.

Specification of Letters Patent. Patented Mar. 17, 1914.

Application filed May 20, 1911. Serial No. 628,430.

To all whom it may concern:

Be it known that I, RICHARD HERBERT PARFITT, a subject of the King of Great Britain, residing at Victoria Works, Tunnel 5 avenue, East Greenwich, in the county of Kent, England, have invented certain new and useful Improvements in Pattern-Cylinders or the like for Use in Connection with the Manufacture of Inlaid Linoleum or other 10 Similar Material, of which the following is a specification.

In the manufacture of inlaid linoleum the various figures that form the pattern are cut out of colored sheets and are assembled upon 15 a backing of canvas. For effecting this purpose it is customary to employ one or other of two kinds of cylinders which are respectively known as positive pattern cylinders and universal pattern cylinders both of 20 which comprise a number of fixed knives, operating in conjunction with movable pusher plates that occupy the spaces bounded by the knives. In the positive pattern cylinders these knives are irregularly formed and 25 spaced in accordance with the particular pattern to be produced, and in the event of the pattern comprising a number of colors, a separate pattern cylinder provided with a 30 different arrangement of knives is required for each color. These pattern cylinders constitute a set, and one set of positive pattern cylinders is capable of producing one design only. The cut material that is not transferred from any one cylinder to the backing 35 is termed "waste" and is returned to suitable machinery by which it is again transformed into the aforesaid sheets. In the universal pattern cylinders the knives are 40 regularly formed and spaced, the spaces bounded by the knives, whether of rectangular, triangular, hexagonal, or other formation comprising units of equal shapes and sizes. In this arrangement all the pattern cylinders in a set are the same, and one set 45 of universal pattern cylinders is capable of producing a number of different designs, the constituent parts of which are made up of varying multiples of the aforesaid units.

The present invention has for its chief object to enable a number of designs, which would hitherto have required a set of positive pattern cylinders for each design, to be produced from one set of pattern cylinders.

According to this invention each cylinder 55 (or equivalent knife carrying device) of a

set of pattern cylinders is built up of (1) similarly arranged groups of knives of a desired pattern forming a complete design of the type hitherto confined to positive pattern cylinders, each group having individual 60 knives adapted to cut complete figures of irregular form, and of (2) short subsidiary knives crossing and connecting together the groups of primary knives and mainly occupying the space which in positive cylinders giving a corresponding design is occupied by the ground of the design, the subsidiary knives being so grouped as to enable (by proper selection of the sections cut out) 70 a great number of different designs based on the primary design of the main knives to be obtained from the same set of cylinders. Each of such designs would hitherto have required a separate set of cylinders. The selection of the sections cut by the knives is 75 effected by any known form of "picking out" device, such as a picking out roller with pusher pins, the design obtained from the cylinders depending upon the arrangement of such pins upon the rollers. The adjacent 80 sections cut from the same sheet if selected, as part of the particular design in process of formation, are joined upon the canvas backing and after the usual pressing operation show no signs of the original division. Any 85 number of pieces of whatever shape that are contiguous to one another can be cut out from one sheet and assembled on a canvas backing as one whole figure.

It is to be understood that it is not desired 90 to limit the invention to cylinders as it is equally applicable to plates, presses or the like that could fulfill the functions of a cylinder.

My invention is illustrated in the accompanying drawings, in which the full lines indicated in Figures 1, 2, 3 and 4 represent four different arrangements of knives which together constitute a set of positive pattern knives. Fig. 5 shows a four color design 95 100 which may be produced by the pattern knives of the preceding figures. Fig. 6 illustrates a set of knives arranged in accordance with this invention for producing not only the design illustrated in Fig. 5 but additional designs such for example as those which are illustrated in Figs. 7, 8 and 9. Fig. 10 shows in diagrammatic form the general arrangement of a cylinder machine for making four color linoleum. 110

Referring first to the known arrangement shown in Figs. 1, 2, 3 and 4 the knives indicated in Fig. 1 cut out the shaded portions marked A from a sheet of material which 5 may for example be red, the portions so cut out being transferred to the canvas backing by the usual pusher pins or other devices ordinarily employed.

The unshaded portions B represent the 10 waste material hereinbefore referred to that is transferred to another machine for remaking into sheets. This material is cut up into suitable sizes for handling, by knives indicated by the dotted lines C which however form no part of the pattern producing 15 knives.

The knives indicated in Figs. 2, 3 and 4 cut out the shaded portions marked A', A², A³ from sheets of material which may for 20 example be blue, green and yellow respectively, the material so cut being transferred to the backing and producing the design indicated in Fig. 5, the unshaded portions B in each figure representing the waste and the 25 dotted lines C indicating the knives for cutting up the same. In the arrangement above described the cylinders, plates, presses or the like that carry the aforesaid knives are not interchangeable and the original form of the 30 design can not be altered, and although each arrangement of knives shown in Figs. 1, 2, 3 and 4 virtually constitutes a different design, no individual design can be utilized owing to the fact that the knives on the remaining 35 cylinders, plates or the like, are incapable of cutting out pieces to replace the waste that would be discarded from such design.

According to this invention in order to 40 produce a design such as that which is illustrated in Fig. 5 each of the four cylinders, plates, presses or the like is provided with an arrangement of knives similar to that indicated in Fig. 6, the full lines representing 45 the knives that produce the design shown in Fig. 5 and the dotted lines indicating knives that are inserted in each cylinder, plate or the like for producing additional designs a few of which are illustrated in Figs. 7, 8 and 9. The main knives in the illustration 50 shown are divided into two chief groups, D' and D², the former group constituting a set of star shaped cells of somewhat complicated pattern, while the group D² consists of stars inclosed in the said cells. The 55 ground between the two chief groups is occupied by the short connecting knives D³ shown in dotted lines. Fig. 6 shows a single knife segment, which is usually cast in one 60 piece and curved to the shape of the knife cylinder, to which it is screwed through any of the convenient spaces between the knives, the longer spaces being generally chosen. It will thus be seen that owing to the various 65 shapes and arrangements of knives being re-

peated in each cylinder, plate or the like, any piece of material ejected from any one cylinder can be replaced by a corresponding piece of material from any of the remaining cylinders, consequently it is possible to eject or to retain any part of an original pattern or to add thereto. The additional knives represented by the dotted lines being all adaptable for producing other designs in addition to serving for cutting up waste.

The cylinder apparatus shown diagrammatically in Fig. 10 illustrates the manner in which this invention may be practically carried into effect. The large central drum E is the one over which passes the backing receiving the colored material and carrying it to the usual pressing apparatus. The four bands F of different colored linoleum substance are carried over the cylinders G arranged at one side of the central drum E. For convenience of illustration the four bands are shown of different thickness to indicate the different colors and the way in which the cut pieces f fit between each other on the drum E. Between the cylinders G and drum E are situated the knife cylinders H, the lower one of which is shown in section to illustrate a method of selecting and ejecting the pieces cut by the knives D. Each of the cylinders G receives a set of 9 knife segments all of the same design, as for instance the segment shown in Fig. 6, so that the complete cylinders are all alike as regards knife pattern. The knives D cut up the band F of colored composition into design units at the point of contact between the cylinders G and H.

Within each cylinder is an ejecting roller J with studs j which meet certain of the ejecting pins K by which the pieces f of colored composition cut by the knives D are ejected and drop into the waste receptacle L. The studs on the roller J are grouped so as to select as waste those pieces which do not enter into the design, the remaining pieces 10 being ejected on to the backing on the central drum E by means of the smooth roller J' which presses out all the pins K left untouched by the studs j. The action in all the knife cylinders is the same, but the rollers J 11 are made so that the design units of the various colored materials are complementary and fit into place on the drum E as the drum and cylinders revolve, in the manner shown diagrammatically in the drawing. By varying the stud arrangement of the rollers J, with similar knife patterns (such for example as are illustrated in Fig. 6) on each knife cylinder a great variety of designs can be produced without any further alteration. 120 These four examples given in Figs. 5, 7, 8 and 9 are only a few out of several hundred which could be prepared from the knife arrangement of Fig. 6, when repeated on each of the knife cylinders.

What I claim and desire to secure by Letters Patent of the United States is:—

In a linoleum machine, a plurality of knife carriers each having thereon a plurality of groups of main knives arranged to cut patterns of complex multi-point design, and a set of subsidiary design cutting knives connecting together said groups of main knives, the knives of each carrier being like

those of all others in design, and an adjustable selective ejecting mechanism for each carrier.

In testimony whereof I affix my signature in presence of two witnesses.

RICHARD HERBERT PARFITT.
